BORING MACHINE WITH ATTACHMENTS

Ewald A. Arp, Minneapolis, Minn., assignor to Tobin-Arp Manufacturing Company, Minneapolis, Minn., a copartnership consisting of Wilbert J. Tobin, Ewald A. Arp, and Henry S. Kedney, Minneapolis, Minn.

Application August 7, 1941, Serial No. 405,773

28 Claims. (Cl. 77—2)

This invention has relation to a boring machine with attachment for clamping articles, such, for example, as connecting rods, in the boring machine so that inner bearing surfaces of the articles or connecting rods can be finished.

An object of the invention is to provide a boring machine with attachment of the nature as stated, designed to incorporate various improved features and characteristics of construction which will be novel both as individual entities of said boring machine with attachment and in combination with each other.

A further object is to provide a boring machine with attachment adapted to the purpose of positioning and clamping an article such as a connecting rod in said boring machine in novel and improved manner so that an internal bearing surface of said article or connecting rod can be accurately finished.

And a further object is to provide a boring machine with attachment of construction as hereinafter explicitly set forth.

With the above objects in view, as well as others which will appear as the specification proceeds, the invention comprises the construction, arrangement and combination of parts as now to be fully described and as hereinafter to be specifically claimed, it being understood that the disclosure herein is merely illustrative and intended in no way in a limiting sense, changes in details of construction and arrangement of parts being permissible so long as within the spirit of the invention and the scope of the claims which follow.

In the accompanying drawing forming a part of this specification,

Fig. 1 is a front elevational view of a boring machine with attachment made according to the invention;

Fig. 2 is a fragmentary horizontal sectional view, partially in elevation, of the machine with attachment of Fig. 1;

Fig. 3 is a fragmentary vertical sectional view, partially in elevation, of said machine with attachment of Fig. 1;

Fig. 4 is an enlarged fragmentary sectional view detailing the clamping nut of the machine with attachment, as well as parts associated with said clamping nut;

Fig. 5 is an enlarged sectional view, taken on line 5—5 in Fig. 1; and

Fig. 6 is a detail sectional view on either of the lines 6—6 in Fig. 2.

With respect to the drawing and the numerals of reference thereon, a frame for the machine

with attachment is denoted at 10 and a support of said frame is denoted at 11. Only a part of the frame 10 is disclosed, and that part includes an upright block, denoted 12, of metal having a forward, desirably vertical, flat surface 13.

A cutter shaft 14 of the boring machine is suitably and conveniently mounted, as at 15, for rotational and endwise movement in the block 12, and said cutter shaft is disposed in right angle relation to the forward, flat surface 13 of said block. The cutter shaft can be rotated and reciprocated in any ordinary or preferred manner, forming no part of the present invention. The front end portion of said cutter shaft is adapted to be projected to position beyond the forward, flat surface 13, as the cutter shaft is disclosed in the drawing, and a usual cutter 16 is adapted to be situated in a cross slot 17 through said front end portion of said cutter shaft and to be releasably retained in said cross slot in any suitable and convenient manner, as by employment of a set screw 18.

A backing member 19, adapted to be engaged by one surface of an article, such as a connecting rod 20, to be operated upon in the machine, is inset into the forward, flat surface 13 of the block 12 and itself includes a forward, flat surface 21 which is as shown disposed slightly forwardly of and parallel to said surface 13. That is, the cutter shaft 14 is perpendicular to the forward, flat surface 21, as well as perpendicular to the forward, flat surface 13.

An article or connecting rod positioner, denoted generally at 22, is adapted to be actuated to cause an internal bearing surface of an article or connecting rod to be operated upon to be accurately centered in the machine with respect to the cutter shaft 14 and its cutter 16, and an article or connecting rod clamping device, represented generally at 23, is adapted to be actuated to cause an article or connecting rod, after centered by said positioner, to be rigidly clamped in its centered position against the backing surface 19 and between said backing surface and the clamping device 23. The positioner 22 is adapted to be removed from the machine after it has been actuated to center an article or connecting rod, as well as after the clamping device 23 has been turned home, but before the commencement of the boring operation of the cutter 16 upon the internal bearing surface of the centered article or connecting rod intended to finish said internal bearing surface.

The clamping device 23 includes a pair of spaced apart, oppositely disposed trunnions 24,

24, each mounted for movement of rotation in a bearing member 25 supported upon the forward wall of the block 12. The trunnions 24 are aligned with each other, and each extends horizontally outwardly away from its corresponding bearing member 25 to position spaced from the machine frame. The outer end of each trunnion pivotally supports, as at 26, an intermediate portion of a vertically disposed lever 27. The levers 27 are supported by the trunnions 24 for pivotal movement in a substantially vertical plane.

The lower end portion of each vertical lever 27 is pivotally connected, as at 28, to the adjacent end of a substantially horizontal, inwardly extending link 29, and the opposite or inner end of each link 29 is pivotally connected, as at 30, to a clamping nut 31.

The clamping nut 31 is rotatably mounted against endwise play or movement upon the outer surface of an internally threaded tubular element 32 itself threadably mounted upon a horizontal externally threaded member 33 fixed in the machine frame as at 34. A spring pressed friction element 35 in the clamping nut 31 and engaged against the external surface of the tubular element 32 is for a purpose to be made plain. A lug 36 upon an arm 37 of said clamping nut 31 and adapted to engage one of the links 29 is also for a purpose to be set forth. Means for rotating the tubular element 32 upon the threaded member 33, thus to cause said tubular element and the clamping nut 31 to be moved inwardly or outwardly of the machine, is constituted as an operating handle 38 integral or rigid with the outer end of said tubular element.

The upper end portion of each vertical lever 27 includes an opening 39 which loosely receives a horizontal guide rod 40. A nut 41 upon the forward end portion of each guide rod 40 is adapted to be engaged by the upper end portion of the corresponding vertical lever 27, at location about the opening 39, and lock nuts 42 upon the guide rods and engaged against the nuts 41 are for insuring the set positions of said nuts.

An intermediate portion of each guide rod 40 is slidably disposed in a guide way 43 of a corresponding guide 44, and each guide 44 is integral or rigid with an inwardly extending, horizontally disposed strip 45 of rigid material or metal slidably mounted in a horizontal guide channel 46 included in a forward portion of the machine frame. The guide channels 46 are in aligned relation to each other at the opposite sides of and just forwardly of the forward surface 13.

Each rigid strip 45 fixedly supports, as at 47, an externally threaded member 48 which is perpendicular to the strip and extends horizontally outwardly away from the forward surface of the machine and is parallel with and in spaced relation to the guide rod 40 at the corresponding side of said machine. In turn, each externally threaded member 48 adjustably supports a tubular element 49 which is mounted upon the externally threaded member for adjustment longitudinally thereof. More explicitly, the tubular elements 49 are threaded upon the horizontal members 48.

Each tubular element 49 pivotally supports, as denoted generally at 50, an intermediate portion of a horizontal clamping lever 51, and the construction and arrangement are such as to preclude longitudinal movement of each of the clamping levers 51 upon its corresponding tubular element 49.

The clamping levers 51 are disposed in aline-

ment with each other at diametrically opposite sides of an article or connecting rod when situated in the machine, and an inner surface 52 of the inner end portion of each clamping lever is adapted to be engaged against an outer portion of the surface of said article or connecting rod which is opposite the backing member 19. The surfaces 52 are diametrically opposite each other, with respect to the article or connecting rod, and the construction and arrangement are such that the inner ends of the clamping levers are at the outer side of and clear of the internal bearing surface of an article or connecting rod when clamped in the machine. See Fig. 2. The forward end of each guide rod 40 is pivotally secured, as at 53, between spaced apart ears 54 upon the outer end of the corresponding clamping lever 51.

The article or connecting rod positioner 22 includes an expander 55 and a plurality of spreader elements 56. The expander 55 is constituted as an annular body 57 and spaced apart extension portions 58 rigid with said annular body. A central longitudinal opening 59 through said annular body 57 is of diameter to be snugly slidably receivable upon the cutter shaft 14, and the extension portions 58 are disposed to clear said cutter shaft. As shown, there are three spreader elements 56 spaced about the expander 55 at 120 degrees apart, and each spreader element includes a longitudinal slot 60 slidably disposed upon the outer marginal portion of one of the extension portions 58 of the expander. The outer edge 61 of each extension portion 58 slants inwardly of the expander in direction away from the annular body of said expander, and said outer edges 61 are spaced equidistantly from the longitudinal axis of the expander. The spreader elements 56 are held to each other and to the extension portions 58 of the expander 55 by an encircling coil spring 62, and the forward end portion 63 of each spreader element is adapted to enter the eye of an article or connecting rod to be centered so that an outer edge 64 of said forward end portion is engaged against the bounding surface of said eye, while an edge 65 of the spreader element, at right angles to the edge 64 and disposed rearwardly of the forward end portion 63, is engaged against the forward surface of said article or connecting rod, as clearly disclosed in Fig. 3. The encircling coil spring 62 normally retains the spreader elements in remote relation to said body portion 57 and engaged with portions of the edges 61 spaced from the body portion.

To center an article or connecting rod, the expander 55 is slid upon the cutter shaft 14 and urged in direction toward the article or connecting rod, while said article or connecting rod is retained adjacent to or contiguous with the backing member 19, until the forward end portions 63 of the spreader elements first enter the eye of the article or connecting rod, the edges 65 next engage the forward surface of said article or connecting rod, and the outer edges 64 finally engage against the bounding surface of said eye by reason of relative movement between the expander 55 and the spreader elements 56 caused by continued inward movement of said expander after engagement of said edges 65 with the article or connecting rod, which continued movement causes spreading action upon said elements 56. At the completion of inward movement of the expander 55, the article or connecting rod is releasably gripped between the backing ele-

ment 19 and the edges 65, and is also centered in the machine for proper finishing of the internal surface of the eye of said article or connecting rod. The construction and arrangement desirably will be such that all elements of the positioner 22 can clear the cutter 16. That is, the positioner can be applied while the cutter is mounted in the cutter shaft. The positioner will be left upon the cutter shaft as in Fig. 3 until the clamping device is turned home, and said positioner will then be removed before the boring operation upon an article or connecting rod is commenced.

The clamping device 23 is adapted to be actuated to cause an article or connecting rod to be clamped in the machine or released therefrom by rotation of the operating handle 38. Assuming said clamping device turned home so that an article or connecting rod is clamped in the machine between the backing member 19 and the surfaces 52 of the clamping levers 51, rotation of said operating handle 38 toward the left in Fig. 1 will cause said surfaces 52 to be moved both away from and clear of said article or connecting rod. With turning movement of the operating handle toward the left, the tubular element 32 will be rotated and moved outwardly of the frame with resultant movement of the surfaces 52 to released position of the article or connecting rod, and when said surfaces 52 release said article or connecting rod, the spring pressed friction element 35 will cause the clamping nut 31 to rotate with said tubular element 32 to cause the lug 36 to be removed from engagement with the underside of one of the links 29 and an arm 68 of the clamping nut to become engaged with a stop 69 upon the machine frame. Such movement of said clamping nut will cause the pivotal connections 30, 30 to be moved toward the center of the machine, thus to cause the guide rods 40, the strips 45 and the clamping levers 51 to be moved outwardly so that said clamping levers and their surfaces 52 are clear of said article or connecting rod and at the opposite sides thereof. Assuming the clamping device in released position, with the lug 36 spaced from the link and the arm 68 engaged with the stop 69 and the clamping levers disposed clear of an article or connecting rod inserted in the machine to be clamped, rotation of the operating handle 38 toward the right will first cause the clamping nut 31 to be rotated, by reason of the friction exerted by the spring pressed element 35, until the links 29, 29 are in alinement and the lug 36 engages a link, thus to cause the surfaces 52 to be moved into position directly in front of the side surfaces of the article or connecting rod, and continued rotation of said operating handle 38 toward the right will cause said surfaces 52 to be turned down against said article or connecting rod. Clearly, movement of the pivotal connections 30, 30 inwardly of the machine causes outward movement of the upper ends of the vertical levers 51, and vice versa. Inward and outward pivotal movements of the vertical levers are of course about the pivotal connections 26. With inward and outward movement of the clamping nut 31 the links 29 are moved toward and away from the machine frame to cause the lower end portions of the vertical levers 27, 27 to be moved in the same direction, with rotation of the trunnions 24, 24 in their bearings. Movement of said lower end portions of the vertical levers 27, 27 in direction toward the machine frame causes the surfaces 52, 52 to be moved to-

ward the article or connecting rod, and vice versa.

The elements 49 are adjustable on the members 48 in order that said elements 49 can be set closer in when a thinner article or connecting rod is to be clamped and farther out when the machine is to receive a thicker article or connecting rod. Desirably, the trunnions 24 are adjustable longitudinally in the bearing members 25 so that the machine can accommodate articles or connecting rods of different widths or diameters. As disclosed, a set screw 67 fixes the position of each trunnion 24 within its bearing member 25, and adjustment of the trunnions in direction lengthwise thereof can be readily accomplished by causing the set screws to be released from the trunnions.

The pivotal connections 30, 30 are at the inner ends of the arms 37 and 68 so that the links 29, 29 will be moved inwardly bodily with inward movement of the clamping nut 31, as will be understood.

What is claimed is:

1. In a machine for boring an internal bearing of an article such as a connecting rod, a cutter shaft adapted to be reciprocated and rotated, a cutter carried by said cutter shaft, and means for releasably securing said article in centered position including a backing member adapted to be engaged by a surface of said article, spaced apart levers having clamping surfaces thereof adapted to be releasably engaged against a surface of the article opposite said backing member, and mechanism for simultaneously actuating said levers to cause their clamping surfaces to be pressingly engaged with and released and withdrawn from said article.

2. In a machine for boring an internal bearing of an article such as a connecting rod, a cutter shaft adapted to be reciprocated and rotated, a cutter carried by said cutter shaft, positioning means for centering said article with respect to said outer shaft and cutter, and means for releasably securing said article in centered position including a backing member adapted to be engaged by a surface of said article, spaced apart levers having clamping surfaces thereof adapted to be releasably engaged against spaced apart portions of a surface of the article opposite said backing member and in spaced relation to said internal bearing, mechanism for simultaneously actuating said levers to cause their clamping surfaces to be concurrently pressingly engaged with and released and withdrawn from said article, and unitary means for actuating said mechanism.

3. In a machine for boring an internal bearing of an article such as a connecting rod, a cutter shaft adapted to be reciprocated and rotated, a cutter carried by said cutter shaft, positioning means for centering said article with respect to said cutter shaft and cutter, and means for releasably securing said article in centered position including a backing member adapted to be engaged by a surface of said article at location spaced from said internal bearing, spaced apart levers having clamping surfaces thereof adapted to be releasably engaged against spaced apart portions of a surface of the article opposite said backing member and in spaced relation to said internal bearing, and mechanism for simultaneously actuating said levers to cause their clamping surfaces to be concurrently pressingly engaged with and released and withdrawn from said article.

4. In a machine for boring an internal bearing

of an article such as a connecting rod, a cutter shaft adapted to be reciprocated and rotated, a cutter carried by said cutter shaft, positioning means for centering said article with respect to said cutter shaft and cutter, and means for releasably securing said article in centered position including a backing member adapted to be engaged by a surface of said article, spaced apart levers having clamping surfaces thereof adapted to be releasably engaged against spaced apart portions of a surface of the article opposite said backing member and in spaced relation to said internal bearing, and mechanism for simultaneously actuating said levers to cause their clamping surfaces to be concurrently pressingly engaged with said spaced apart portions of said surface of said article and simultaneously released from the spaced apart portions of the surface and withdrawn to clearing relation of said article.

5. In a machine for boring an internal bearing of an article such as a connecting rod, a cutter shaft adapted to be reciprocated and rotated, a cutter carried by said cutter shaft, and means for releasably securing said article in centered position including a backing member adapted to be engaged by a surface of said article in spaced relation to said internal bearing, spaced apart levers having clamping surfaces thereof adapted to be releasably engaged against spaced apart portions of a surface of the article opposite said backing member and in spaced relation to said internal bearing, an entity adapted to be actuated to cause the clamping surfaces of said levers to be concurrently pressingly engaged against said spaced apart portions of said surface of said article and to be concurrently released from the spaced apart portions of the surface and withdrawn from the article, and means for actuating said entity.

6. In a machine for boring an internal bearing of an article such as a connecting rod, a cutter shaft adapted to be reciprocated and rotated, a cutter carried by said cutter shaft, positioning means for centering said article with respect to said cutter shaft and cutter, and means for releasably securing said article in centered position including a backing member adapted to be engaged by a surface of said article, spaced apart levers having clamping surfaces thereof adapted to be releasably engaged against spaced apart portions of a surface of the article opposite said backing member and in spaced relation to said internal bearing, and an entity adapted to be rotated to cause the clamping surfaces of said levers to be concurrently pressingly engaged against said spaced apart portions of said surface of said article with rotation of said entity in one direction and to be concurrently released from the spaced apart portions of the surface and withdrawn from the article with rotation of said entity in opposite direction.

7. In a machine for boring an internal bearing of an article such as a connecting rod, a cutter shaft adapted to be reciprocated and rotated, a cutter carried by said cutter shaft, positioning means for centering said article with respect to said cutter shaft and cutter, and means for releasably securing said article in centered position including a backing member adapted to be engaged by a surface of said article in spaced relation to said internal bearing, spaced apart levers having clamping surfaces thereof adapted to be releasably engaged against spaced apart portions of a surface of the article opposite said backing member and in spaced relation to said internal

bearing, and an entity including an actuating nut and a link device adapted to be actuated to cause the clamping surfaces of said levers to be moved in a straight path toward and against said article when said actuating nut is caused to be moved in one direction and to be released from said article and withdrawn from the location of the article when said actuating nut is caused to be moved in a different direction.

10. In a machine for boring an internal bearing of an article such as a connecting rod, a cutter shaft adapted to be reciprocated and rotated, a cutter carried by said cutter shaft, positioning means for centering said article with respect to said cutter shaft and cutter, and means for releasably securing said article in centered position including a backing member adapted to be engaged by a surface of said article, spaced apart levers having clamping surfaces thereof adapted to be releasably engaged against spaced apart portions of a surface of the article opposite said backing member and in spaced relation to said internal bearing, and an entity including an actuating nut and a link device adapted to be operated to cause the clamping surfaces of said levers to be first moved to the location of said article and then moved in a straight path toward and against said article when said actuating nut is caused to be moved in one direction and to be released from said article and withdrawn from the location of the article when said actuating nut is caused to be moved in a different direction.

15. In a machine for boring an internal bearing of an article such as a connecting rod, a cutter shaft adapted to be reciprocated and rotated, a cutter carried by said cutter shaft, positioning means for centering said article with respect to said cutter shaft and cutter, and means for releasably securing said article in centered position including a backing member adapted to be engaged with a surface of said article, spaced apart levers having clamping surfaces thereof adapted to be releasably engaged against spaced apart portions of a surface of the article opposite said backing member and in spaced relation to said internal bearing, and mechanism for simultaneously actuating said levers to cause their clamping surfaces to be moved toward and away from each other and at angular relation to the direction in which said clamping surfaces are moved toward and away from each other and concurrently pressingly engaged with and released and withdrawn from said article.

20. In a machine for boring an internal bearing of an article such as a connecting rod, a cutter shaft adapted to be reciprocated and rotated, a cutter carried by said cutter shaft, positioning means for centering said article with respect to said cutter shaft and cutter, and means for releasably securing said article in centered position including a backing member adapted to be engaged by a surface of said article in spaced relation to said internal bearing, spaced apart levers having clamping surfaces thereof adapted to be releasably engaged against spaced apart portions of a surface of the article opposite said backing member and in spaced relation to said internal bearing, mechanism for simultaneously actuating said levers to cause their clamping surfaces to be moved toward and away from each other and at angular relation to the direction in which said clamping surfaces are moved toward and away from each other and concurrently pressingly engaged with said spaced apart portions of said surface of said article and simul-

aneously released from the spaced apart portions and withdrawn to clearing relation of the article, and a rotatable member for actuating said mechanism.

11. In a machine for boring an internal bearing of an article such as a connecting rod, a cutter shaft adapted to be reciprocated and rotated, a cutter carried by said cutter shaft, positioning means for centering said article with respect to said cutter shaft and cutter, and means for releasably securing said article in centered position including a backing member adapted to be engaged by a surface of said article, spaced apart levers having clamping surfaces thereof adapted to be releasably engaged against spaced apart portions of a surface of the article opposite said backing member and in spaced relation to said internal bearing, and an entity including an actuating nut and a link device adapted to be operated to cause the clamping surfaces of said levers to be moved toward and away from each other and at angular relation to the direction in which said clamping surfaces are moved toward and away from each other with rotation of the actuating nut in opposite directions and concurrently pressingly engaged with said spaced apart portions of said surface of said article and simultaneously released from the spaced apart portions and withdrawn to clearing relation of the article.

12. In a machine for boring an internal bearing of an article such as a connecting rod, a cutter shaft adapted to be reciprocated and rotated, a cutter carried by said cutter shaft, positioning means for centering said article with respect to said cutter shaft and cutter, and means for releasably securing said article in centered position including a backing member adapted to be engaged by a surface of said article, spaced apart levers having clamping surfaces thereof adapted to be releasably engaged against spaced apart portions of a surface of the article opposite said backing member and in spaced relation to said internal bearing, a clamping nut, and link devices between said spaced apart levers and said clamping nut.

13. In a machine for boring an internal bearing of an article such as a connecting rod, a cutter shaft adapted to be reciprocated and rotated, a cutter carried by said cutter shaft, positioning means for centering said article with respect to said cutter and cutter shaft, and means for releasably securing said article in centered position including a backing member adapted to be engaged by a surface of said article, spaced apart levers having clamping surfaces thereof adapted to be releasably engaged against spaced apart portions of a surface of the article opposite said backing member and in spaced relation to said internal bearing, a clamping nut, and link devices between said spaced apart levers and said clamping nut, said clamping nut being adapted to be actuated in opposite directions to cause the clamping surfaces of said levers to be moved toward and away from each other and at angular relation to the direction in which said clamping surfaces are moved toward and away from each other and to be concurrently pressingly engaged against said spaced apart portions of said surface of said article and simultaneously released from the spaced apart portions and withdrawn to clearing relation of the article.

14. In a machine of the character described, a frame, guide means upon said frame, a strip of material slidably mounted in said guide means,

a clamping lever pivoted upon said strip and including a clamping surface at one side of its axis, a guide upon said strip, a guide rod slidably mounted in said guide and pivotally connected to

5 a portion of said clamping lever at the side of its axis opposite its clamping surface, an element fixed upon said guide rod between said strip and clamping lever, a trunnion, an actuating lever having an intermediate portion thereof pivotally supported upon said trunnion for universal movement of the actuating lever, said actuating lever having an end portion thereof loosely arranged upon said guide rod between said fixed element and said strip, an actuating nut upon said frame, and a link pivoted to said actuating nut and to an end portion of said actuating lever at the side of said trunnion opposite said guide rod.

15. In a machine of the character described, a frame, guide means upon said frame, a strip of material slidably mounted in said guide means, a clamping lever pivoted upon said strip and including a clamping surface at one side of its axis, a guide upon said strip, a guide rod slidably mounted in said guide and pivotally connected to a portion of said clamping lever at the side of its axis opposite its clamping surface, an element fixed upon said guide rod between said strip and clamping lever, a trunnion, an actuating lever having an intermediate portion thereof pivotally supported upon said trunnion for universal movement of the actuating lever, said actuating lever having an end portion thereof loosely arranged upon said guide rod between said fixed element and said strip, an actuating nut upon said frame, a link pivoted to said actuating nut and to an end portion of said actuating lever at the side of said trunnion opposite said guide rod, and an arm upon said actuating nut engaging said link at a location spaced outwardly of the pivotal connection between the actuating nut and link.

16. In a machine of the character described, a frame, oppositely disposed guide channels upon said frame, a strip of material slidably mounted in each of said guide channels, a clamping lever pivotally supported upon each of said strips and including a clamping surface at one side of its axis, a guide upon each of said strips, a guide rod slidably mounted in each of said guides and pivotally connected to a portion of one of said clamping levers at the side of its axis opposite its clamping surface, an element fixed upon each of said guide rods between the corresponding strip and clamping lever, oppositely disposed trunnions, oppositely disposed actuating levers including an actuating lever having an intermediate portion thereof pivotally supported upon each of said trunnions for universal movement of the actuating lever, each of said actuating levers including an end portion thereof loosely arranged upon one of said guide rods between the corresponding fixed element and strip, an actuating nut upon said frame, and links pivoted upon said actuating nut and pivotally connected to end portions of said actuating levers at the sides of said trunnions opposite said guide rods.

17. In a machine of the character described, a frame, oppositely disposed guide channels upon said frame, a strip of material slidably mounted in each of said guide channels, a clamping lever pivotally supported upon each of said strips and including a clamping surface at one side of its axis, a guide upon each of said strips, a guide rod slidably mounted in each of said guides and pivotally connected to a portion of one of said

clamping levers at the side of its axis opposite its clamping surface, an element fixed upon each of said guide rods between the corresponding strip and clamping lever, oppositely disposed trunnions, oppositely disposed actuating levers including an actuating lever having an intermediate portion thereof pivotally supported upon each of said trunnions for universal movement of the actuating lever, each of said actuating levers including an end portion thereof loosely arranged upon one of said guide rods between the corresponding fixed element and strip, a threaded member upon said frame, a member upon said threaded member adapted to be moved inwardly of the frame with rotation of the member in one direction and outwardly of said frame with rotation of the member in opposite direction, a nut rotatable with and upon said member, links pivoted upon said nut and pivotally connected to end portions of said actuating levers at the sides of said trunnions opposite said guide rods, friction producing means between said nut and said member, an arm upon said nut adapted to engage one of said links, a stop upon said frame, and means upon said nut adapted to engage said stop.

18. In a machine of the character described, a frame, oppositely disposed guide channels upon said frame, a strip of material slidably mounted in each of said guide channels, a clamping lever pivotally supported upon each of said strips and including a clamping surface at one side of its axis, a guide upon each of said strips, a guide rod slidably mounted in each of said guides and pivotally connected to a portion of one of said clamping levers at the side of its axis opposite its clamping surface, an element fixed upon each of said guide rods between the corresponding strip and clamping lever, oppositely disposed trunnions, oppositely disposed actuating levers including an actuating lever having an intermediate portion thereof pivotally supported upon each of said trunnions for universal movement of the actuating lever, each of said actuating levers including an end portion thereof loosely arranged upon one of said guide rods between the corresponding fixed element and strip, a threaded member upon said frame, a member upon said threaded member adapted to be moved inwardly of the frame with rotation of said member in one direction and outwardly of said frame with rotation of the member in opposite direction, a nut rotatable with and upon said member, links pivoted upon said nut and pivotally connected to end portions of said actuating levers at the sides of said levers opposite said guide rods, friction producing means between said nut and said member, arms upon said nut including an arm adjacent the outer side of each of said links at location spaced outwardly of the pivotal connections between the nut and the links, one of said arms including means adapted to engage one of said links to preclude rotation of said nut with said member, and a stop upon said frame adapted to be engaged by one of said arms to preclude rotation of the nut with the member, said nut being adapted to have limited movement of rotation with said member.

19. In a machine for boring an internal bearing of an article such as a connecting rod, a cutter shaft adapted to be reciprocated and rotated, a cutter carried by said cutter shaft, positioning means for centering said article with respect to said cutter shaft and cutter, and means for releasably securing said article in centered position including a backing member adapted to

be engaged by a surface of said article, spaced apart levers having clamping surfaces thereof adapted to be releasably engaged against a surface of the article opposite said backing member, mechanism for actuating said levers to cause their clamping surfaces to be simultaneously pressingly engaged with and released and withdrawn from said article, and means for actuating said mechanism.

20. In a machine for boring an internal bearing of an article such as a connecting rod, a cutter shaft adapted to be reciprocated and rotated, a cutter carried by said cutter shaft, positioning means for centering said article with respect to said cutter shaft and cutter, and means for releasably securing said article in centered position including a backing member adapted to be engaged by a surface of said article, spaced apart levers having clamping surfaces thereof adapted to be releasably engaged against spaced apart portions of a surface of the article opposite said backing member and in spaced relation to said internal bearing, mechanism for simultaneously actuating said levers to cause their clamping surfaces to be concurrently pressingly engaged with said spaced apart portions of said surface of said article and simultaneously released from the spaced apart portions of the surface and withdrawn to clearing relation of said article, and means for actuating said mechanism.

21. In a machine for boring an internal bearing of an article such as a connecting rod, a cutter shaft adapted to be reciprocated and rotated, a cutter carried by said cutter shaft, positioning means for centering said article with respect to said cutter shaft and cutter, and means for releasably securing said article in centered position including a backing member adapted to be engaged by a surface of said article, spaced apart levers having clamping surfaces thereof adapted to be releasably engaged against spaced apart portions of a surface of the article opposite said backing member and in spaced relation to said internal bearing, mechanism adapted to be actuated to cause the clamping surfaces of said levers to be concurrently pressingly engaged against said spaced apart portions of said surface of said article and to be concurrently released from the spaced apart portions of the surface and withdrawn from the article, and means adapted to be rotated in opposite directions for actuating said mechanism.

22. In a machine for boring an internal bearing of an article such as a connecting rod, a cutter shaft adapted to be reciprocated and rotated, a cutter movable with said cutter shaft, and means for releasably securing said article in centered position relatively to said cutter shaft and cutter including a backing member having a surface thereof disposed perpendicular to said cutter shaft adapted to be engaged by a surface of said article, spaced apart clamping levers adapted to be engaged against the surface of the article opposite said backing member, mechanism for actuating said clamping levers, and means for actuating said mechanism.

23. In a machine for boring an internal bearing of an article such as a connecting rod, a cutter shaft adapted to be reciprocated and rotated, a cutter carried by said cutter shaft, positioning means for centering said article with respect to said cutter shaft and cutter, and means for releasably securing said article in centered position including a backing member having a sur-

face thereof disposed perpendicular to said cutter shaft adapted to be engaged by a surface of said article, spaced apart levers having clamping surfaces thereof adapted to be releasably engaged against a surface of the article opposite said backing member, mechanism for causing the clamping surfaces of said levers to be simultaneously pressingly engaged with and released from said article, and means for actuating said mechanism.

24. In a machine for boring an internal bearing of an article such as a connecting rod, a cutter shaft adapted to be reciprocated and rotated, a cutter movable with said cutter shaft, and means for releasably securing said article in centered position relatively to said cutter shaft and cutter including a backing member having a surface thereof disposed perpendicular to said cutter shaft adapted to be engaged by a surface of said article, and a clamping device including spaced apart clamping levers adapted to be engaged against a surface of the article opposite said backing member, and mechanism for simultaneously actuating said clamping levers.

25. In a machine for boring an internal bearing of an article such as a connecting rod, a cutter shaft adapted to be reciprocated and rotated, a cutter carried by said cutter shaft, and means for releasably securing said article in centered position relatively to said cutter shaft and cutter including a backing member having a surface thereof disposed perpendicular to said cutter shaft adapted to be engaged by a surface of said article, spaced apart levers having clamping surfaces thereof adapted to be releasably engaged against a surface of the article opposite said backing member, and mechanism for simultaneously actuating said levers to cause their clamping surfaces to be pressingly engaged with and released from said article.

26. In a machine for boring an internal bearing of an article such as a connecting rod, a cutter shaft adapted to be reciprocated and rotated, a cutter carried by said cutter shaft, positioning means for centering said article with respect to said cutter shaft and cutter, and means for releasably securing said article in centered position including a backing member having a surface thereof disposed perpendicular to said cutter shaft adapted to be engaged by a surface of said article, spaced apart levers having clamping surfaces thereof adapted to be releasably en-

gaged against a surface of the article opposite said backing member, mechanism for actuating said levers to cause their clamping surfaces to be simultaneously pressingly engaged with and released and withdrawn from said article, and means for actuating said mechanism.

27. In a machine for boring an internal bearing of an article such as a connecting rod, a cutter shaft adapted to be reciprocated and rotated, 10 a cutter carried by said cutter shaft, and means for releasably securing said article in centered position relative to said cutter shaft and cutter including a backing member having a surface thereof disposed perpendicular to said cutter shaft adapted to be engaged by a surface of said article, spaced apart levers having clamping surfaces thereof adapted to be releasably engaged against spaced apart portions of a surface of the article opposite said backing member and in 15 spaced relation to said internal bearing, mechanism for simultaneously actuating said levers to cause their clamping surfaces to be concurrently pressingly engaged with said spaced apart portions of said surface of said article and simultaneously released from the spaced apart portions of the surface and withdrawn to clearing 20 relation of said article, and means for actuating said mechanism.

28. In a machine for boring an internal bearing 30 of an article such as a connecting rod, a cutter shaft adapted to be reciprocated and rotated, a cutter carried by said cutter shaft, and means for releasably securing said article in centered position relatively to said cutter shaft and cutter including a backing member having a surface thereof disposed perpendicular to said cutter shaft adapted to be engaged by a surface of said article, spaced apart levers having clamping surfaces thereof adapted to be releasably engaged against spaced apart portion of a surface 35 of the article opposite said backing member and in spaced relation to said internal bearing, mechanism adapted to be actuated to cause the clamping surfaces of said levers to be concurrently pressingly engaged against said spaced apart portions of said surface of said article and to be concurrently released from the spaced apart portions of the surface and withdrawn from the article, and means adapted to be rotated in opposite directions for actuating said mechanism.
